UNITED STATES PATENT OFFICE.

RUDOLPH THIEM, OF HAMILTON, OHIO, ASSIGNOR TO ATLANTA STOVE WORKS, OF ATLANTA, GEORGIA, A CORPORATION OF GEORGIA.

DESIGN FOR A STOVE.

42,790.

Specification for Design.

Patented July 9, 1912.

Application filed March 4, 1912. Serial No. 681,643. Term of patent 14 years.

To all whom it may concern:

Be it known that I, RUDOLPH THIEM, a citizen of the United States, residing at Hamilton, in the county of Butler and State of Ohio, have invented a new, original, and ornamental Design for Stoves, of which the following is a specification, reference being had to the accompanying drawing, forming part thereof.

The figure is a perspective view of a stove,

showing my new design for the ornamentation thereof.

I claim:

The ornamental design for a stove, as shown.

RUDOLPH THIEM.
